(57) **CLAIM**

The ornamental design for an oscillating tool, as shown and described.

DESCRIPTION

FIG. 1 is a top perspective view of an oscillating tool in accordance with the new design;

FIG. 2 is a top view thereof;

FIG. 3 is a right side elevation view thereof;

FIG. 4 is a left side elevation view thereof;

FIG. 5 is a bottom view thereof;

FIG. 6 is a front view thereof; and,

FIG. 7 is a rear view thereof.

The broken lines shown in the drawings represent unclaimed portions of the portable oscillating tool, and form no part of the claimed design.
